UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed February 2, 1925, Serial No. 6,477. Renewed April 24, 1930.

My invention relates to mining machines and more particularly to coal mining machines of the wheel mounted type adapted to operate from the mine trackway.

5 An object of my invention is to provide an improved mining machine. Another object of my invention is to provide an improved mining machine of the wheeled truck mounted type adapted to operate from the mine trackway. Still another object of my invention is to provide an improved mining machine of the so-called universal type of a low, compact character especially adapted to use in mines having narrow or low veins 10 wherein improved and simplified operating mechanism for the cutting mechanism, improved propulsion mechanism, and improved raising and lowering means for the cutting mechanism are provided. A further 15 object of my invention is to provide an improved mining machine of the combined horizontal and vertical cutter type wherein the cutter bar may be expeditiously adjusted in a plurality of operative positions. A still 20 further object of my invention is to provide an improved mining machine of the wheel mounted type having improved elevating mechanism for the machine body wherein the truck wheels may be driven irrespective of 25 the elevation or angle in altitude of the body relative thereto. A still further object of my invention is to provide an improved tilting means for the cutter bar. Another object of my invention is to provide an im- 30 proved, simplified, and exceedingly compact general arrangement of parts whereby the machine may be operated with facility and expeditiously in mines having narrow or low veins. These and other objects and advan- 35 tages of my invention will, however, herein- 40 after more fully appear.

In the accompanying drawings I have shown for purposes of illustration one form and two modifications thereof which my in- 45 vention may assume in practice.

In these drawings,—

Fig. 1 is a plan view of a mining machine constructed in accordance with one illustrative form of my invention, the view being 50 partially broken away to facilitate illustra-

tion and the cutter bar being shown in horizontal cutting position.

Fig. 2 is a side elevational view of the machine shown in Fig. 1, the cutter bar and machine body being shown in its elevated position. 55

Fig. 3 is an enlarged, vertical, longitudinally extending, sectional view through the improved cutting mechanism, the view being taken substantially on line 3—3 of Figs. 60 1 and 5.

Fig. 4 is a vertical, transverse sectional view taken substantially on line 4—4 of Fig. 3.

Fig. 5 is an enlarged plan view of the forward portion of the machine shown in Fig. 65 1, the view being partially broken away in section to illustrate certain details of the construction.

Fig. 6 is an enlarged plan view of the central feeding portion of the machine shown in Fig. 1, the view being partially broken away in section to illustrate certain details. 70

Fig. 7 is a transverse, vertical detail sectional view taken substantially on line 7—7 75 of Fig. 6.

Fig. 8 is a vertical, longitudinally extending, sectional view taken substantially on line 8—8 of Fig. 6.

Fig. 9 is an enlarged, vertical, longitudinally extending, sectional view through a portion of the improved propulsion means, the view being taken substantially on line 9—9 of Figs. 1 and 6. 80

Fig. 10 is a transverse, vertical sectional view taken substantially on line 10—10 of Fig. 9. 85

Fig. 11 is a diagrammatic sectional view illustrating the improved elevating and bar tilting mechanism, the mechanism being 90 shown in a plurality of positions.

Fig. 12 is an enlarged, transverse, vertical sectional view taken substantially on line 12—12 of Fig. 2.

Fig. 13 is a transverse, vertical sectional view illustrating the improved means for bodily rotating the machine frame, the view being taken substantially on line 13—13 of Fig. 2. 95

Fig. 14 is a detail sectional view through 100

the friction device for retarding rotation of the bar swinging gears, the view being taken substantially on line 14—14 of Fig. 5.

Fig. 15 is a detail view of a portion of the improved cutter chain clutch controlling mechanism.

Fig. 16 is a detail sectional view illustrating the improved tension controlling means for the cable reel driving member.

Fig. 17 is a detail view of a modified form of the machine frame rotating mechanism.

Fig. 18 is a modified form of the operating mechanism for the elevating mechanism.

In this illustrative form of my invention I have shown a mining machine 1 of the so-called universal type which, as an entirety, comprises cutting mechanism 2, improved truck driving mechanism 3, and improved elevating and bar tilting mechanism 4. The cutting mechanism driving mechanism and the truck driving mechanism are disposed within an elongated machine frame 5 of generally rectangular shape comprised of three sections, i. e. a cutting mechanism carrying section 6, a motor section 7, and a section 8 housing the propulsion mechanism and cutting mechanism adjusting mechanism, the motor section 7 being interposed between the sections 6 and 8 to which it is rigidly secured by means of spacing or bearing members 9 and 10. The bearing members 9 and 10 are provided with cylindrical longitudinally spaced bearing surfaces 11 (Fig. 12) disposed coaxially with the major axis of the machine frame and these bearing members are journaled within suitable upper and lower semi-circular bearing sleeves 12 and 13, the latter of which are carried by depending brackets or supporting frame members 14 and 15 secured, as by bolts 16, to parallel longitudinally extending frame or angle members 17 and 18 which hold the brackets 14 and 15 in rigid relation and form supports for certain other portions of the machine as hereinafter described. The upper bearing sleeves are carried within clamping members 19 pivoted, as at 20, on the bracket members 14 and 15 and which are adapted to be held in clamping position by suitable adjustable screws 21. These clamping members are adapted to maintain the machine body in any adjusted position relative to the frame members 14 and 15. Dowel pins 22 are provided for preventing displacement of the sleeves. As illustrated, the frame members 14 and 15 are provided with horizontally disposed, transverse, laterally spaced bores 23 formed within suitable clamping members and within which bores sleeve members 24 are inserted forming bearings for parallel supporting arms 25 and 26 in turn carrying any suitable roller bearings 27 and axles 28 and 29 journaled therein. The outer ends of these axles have secured thereto by suitable nut and washer connections 30, truck wheels 31 held

in suitable spaced relation by means of spacing sleeve 32, the arms 25 and 26 and wheels 31 constituting the supporting means for the machine.

In specifically describing my improved cutting mechanism, generally designated 2, it will herein be noted that housed within the motor section 7 is a suitable driving motor 35, herein of the usual reversible electric type, having a longitudinally extending horizontal armature shaft 36 journaled within suitable ball bearings 37 (Fig. 3) carried by a motor head member 38 suitably secured within a bore 39 formed within the bearing section 9. The shaft 36 has secured thereto at its forward end a coaxially disposed hollow shaft 40 journaled in suitable bearings 41 carried within a head member 42, similar to the head member 38 and longitudinally spaced therefrom, carried within a bore 43 formed in the forward end of the frame member 9. A suitable screw 44 extends coaxially through the hollow shaft 40 and engages a threaded reduced portion 45 formed on the armature shaft 36, thus holding the shafts 40 and 36 in rigid operative relation. The shaft 40 has formed thereon at its forward end, in front of the bearing 41, a suitable spur pinion 46. As illustrated, the pinion 46 is internally bored, as at 47, to receive a suitable ball bearing 48 within which, and a bearing 49 carried by the frame section 6, a shaft 50 is journaled and disposed coaxially with shafts 40 and 36. The shaft 50 has formed thereon a spur gear 51 disposed coaxially with the pinion 46 and this gear 51 is adapted to be selectively connected, by means of an internal coaxial shipper gear 52 formed on a flanged shipper member 53, in driving relation with the pinion 46. The shipper member 53 is adapted to be actuated longitudinally by means of a shipper yoke 54 in the form of a bell crank pivoted, as at 55 (Figs. 4 and 5), on a vertical axis within the machine frame and this bell crank is provided with radial arms 56 and 57 adapted to cooperate with the shipper member 53 and a bifurcated member 58, respectively. The bifurcated member 58 is adapted to engage a vertical pin 59 upon the arm 57 and is suitably carried by a cylindrical member 60 slidably mounted within a sleeve 61 in turn mounted within a transversely disposed bore 62 formed in the side of the frame section 6. Moreover, the sleeve 61 has secured thereto, as by radially extending studs 63, an operating member or grasping portion 64 and one of the studs is provided with an inwardly projecting pin adapted to cooperate with a cam slot 65 formed within the member 60. Furthermore, the member 60 is provided with an upstanding portion 66 having secured, as at 67 at its upper end, a transversely disposed rod 68 which is, in turn, secured at its opposite end within a cylindrical member 69 similar to the member 60 and likewise provided

with an operating portion 70 disposed at the opposite side of the machine frame from the portion 60 thus enabling the operator to actuate the clutch from either side of the machine.

5 As illustrated, the shaft 50 has formed thereon a bevel pinion 71 which meshes with a bevel gear 72 rotatable on an axis perpendicular to the axis of the armature shaft and the gear 72 is journaled in suitable spaced 70 bearings 73 carried within the machine frame. The bevel gear 72 has formed thereon a spur pinion 74 which meshes with a large spur gear 75. The gear 75 is provided with a lateral, annular, depending sleeve 76 journaled on spaced bearings 77 surrounding and disposed coaxially with a cutter chain driving shaft 78 disposed on an axis parallel with the axis of the gear 74 and journaled at its opposite ends within suitable ball bearings 20 79 and 80, the former of which are carried within a portion of the frame section 6 while the latter are disposed within a bore 81 formed within a circular bearing portion 82 formed integral with the cutter bar 83.

25 The shaft 78 has secured thereto at one end, as by a suitable key and a radially expanding split washer connection 84, a cutter chain driving sprocket 85, of a well known form, which is adapted to be driven through suitable 75 clutch connections, hereinafter described, by the motor driven gear 75. A cutter bit carrying cutter chain 86 is adapted to be circulated about the outer edges of the cutter bar 83 and is driven by the sprocket 30 85 in the usual manner. As illustrated, a resiliently positioned annular packing ring 87 is disposed between the cylindrical portion 82 and the sprocket 85 and this member 87 prevents the entry of any foreign substance and thus prevents damage to and excessive wear of the moving parts of the machine. The circular bearing portion 82 of the cutter bar is disposed within suitable spaced cylindrical bearing sleeves 88 supported by an annular portion 89 of the machine frame and has secured thereto, by a radially expanding split washer connection 40 90 an annular bearing member 91 which receives the thrust of the cutter bar. The clutch for connecting the gear 75 and the sprocket 85 in driving relation comprises a gear 92 secured to the shaft 78, intermediate its ends, as by a key 92' and a gear 93 held in operative 45 relation with the gear 75 by means of a semi-permanent clutch 93', which gear is journaled upon a bearing sleeve 94 surrounding the shaft 78 and these gears 92 and 93 are adapted to be connected in driving relation by means of a sliding internal gear 95 formed on a flanged shipper member 96. As 50 illustrated, the shipper member 96 is adapted to be reciprocated longitudinally of the shaft 78 by means of a shipper yoke 96' carried on a shaft 97 journaled within laterally spaced bearing members 98 suitably secured 55 to a portion of the machine frame 6. One end of the shaft 97 has secured thereto an arm or lever 99 provided with a slotted end portion 100 which cooperates with an eccentric 70 101 secured to a shaft 102 journaled within the frame sections and which has secured thereto an operating lever 103 which is adapted to be held in its different positions by means of a manually operable spring 75 104. It will thus be evident that by suitably manipulating the lever 103 the gear 93 and consequently the gear 75 driven by said motor 35 and the sprocket 85 may be connected in driving relation at the will of the operator, thus permitting the cutter chain to be rotated or remain idle.

In my improved cutter bar swinging mechanism it will herein be observed that the cutter bar 83 is adapted to be swung or slued through suitable mechanism hereinafter described of the same general type as that disclosed in my copending application, Serial No. 694,139, filed Feb. 20, 1924, at a slow or cutting speed in one direction or at a fast or positioning speed in the opposite direction. 80 In specifically describing the slow or cutting speed driving mechanism it will be noted that the gear 75 is meshed with a spur pinion 105 which has secured thereto a worm 106 having teeth of slight lead and which meshes with a worm gear 107. The worm gear 107 has keyed thereto, as at 108, an annular member 109 journaled on ball bearings 110 carried by the frame section 6. A friction clutch, generally 85 designated 111, is disposed within the worm gear 107 and this clutch comprises friction disks of usual form certain of which are carried by the member 109 while others are carried by a spider member 112 suitably keyed to one end of a transversely disposed shaft 113 journaled within suitable sets of spaced bearings 114 carried by the machine frame. A plate member 115 is provided for applying pressure to the friction disks and this member 90 is provided with a central bore 116 within which a coiled spring 117 is disposed adapted to react on a washer 118 engaging the member 115 and the hub of a hand wheel or operating member 119, respectively. The hand wheel 119 is suitably secured to a transversely disposed, coaxial, threaded operating shaft 120 disposed transversely through and threaded within the shaft 113. It will thus be evident 95 that the load of the pressure applied by the hand wheel 119 is transmitted through and is limited by the coiled spring 117, thereby preventing excessive strain being applied to the driving mechanism and the motor, for instance, when extremely hard material is encountered by the cutter chain. As illustrated, a worm 121 is keyed, as at 122, to the shaft 113 and this worm is meshed with a worm gear 123 bolted at 124 to an annular hub 125 keyed at 126 to a shaft 127 disposed 100 parallel with and in front of the shaft 78. 120

The shaft 127 is journaled in suitable spaced bearings 128 at its ends and is held in position by a suitable radially expanding split washer 129 similar to the washer 84 heretofore described. The shaft 127 has formed thereon a spur pinion 130 which meshes with a large spur gear 131 bolted, as at 132, to a housing or cutter chain guard portion 133 formed on the cutter bar 83. Furthermore, it will be observed that the gear 131 is internally grooved, as at 134, within which groove a guide plate 135 projects, this plate being suitably secured as by bolts 136, to the frame section 6. From the foregoing description it will be evident that when the friction clutch 111 is applied power will be transmitted from the motor 35 through pinion 71, gear 72, pinion 74, gear 75, spur pinion 105, worm 106, worm gear 107, spider 112, shaft 113, worm 121, worm gear 123, spur pinion 130 meshing with the internal gear 131 thereby swinging the cutter bar in a counter-clockwise direction as viewed in Fig. 5 at a slow or cutting speed. It will also be evident that by varying the pressure applied to the clutch disks any suitable variants of such speed may be obtained. Referring particularly to the fast speed bar swinging mechanism it will herein be noted that a pinion 137 meshes with the spur gear 75, and this pinion is oppositely spaced relative to the gear 105 and with respect to the axis of the gear 75. The pinion 137 has secured thereto and rotatable therewith a worm 138 having threads of steeper lead than the threads of the worm 106, and this worm meshes with a worm gear 139 driven through a friction clutch, not shown, similar to the clutch 111 and operated by a suitable hand wheel or operating member 140 and this worm gear 139 is adapted to drive, through the friction clutch, the worm 121 keyed to the shaft 113. From the foregoing description it will be evident that when the clutch connecting the worm gear 139 in driving relation with the worm 121 is applied and the clutch 111 is released, power will be transmitted from the motor 35 through the pinion 71, gear 72, pinion 74, gear 75, pinion 137, worm 138, worm gear 139, worm 121, worm gear 123, and pinion 130 meshing with the internal gear 131, thus swinging the bar in an opposite direction at a fast or positioning speed. It will also be evident that by slipping the clutch controlling the fast feed driving mechanism any suitable variants of such speed may be obtained. Interposed between the bearings 114 of each set of bearings 114 for the gears 107 and 139 is a friction device, generally designated 141, which comprises a plurality of semi-circular plate members 142 keyed to the shaft 113, as at 143, and reacting between these members 142 are suitable coiled springs 144 which force the members 142 outwardly against a bore 145 formed within the frame section 6 frictionally engaging the

latter, thus retarding rotation of the shaft 113 and worm 121 when the friction clutches controlling the gears 107, 139 are inoperative, thereby preventing unintentional rotation of the gear 121 at that time.

In my improved feeding or propulsion mechanism it will herein be noted that the rear end of the armature shaft 36 is journaled in suitable ball bearings 147 carried within a suitable head member 148 and this shaft has secured thereto as by a bolt connection 149 a clutch element 150 provided with internal clutch teeth adapted to engage teeth 151 formed on a longitudinally extending shaft 152 disposed coaxially with the armature shaft and which is in turn journaled at its rear end in a bearing 153 suitably carried by the spacing or bearing member 10. The rear end of the shaft 152 has suitably secured thereto a pinion 154 which is adapted to drive the truck wheels 31 through improved transmission mechanism to be hereinafter described including transmission gearing and controlling clutches substantially similar to that described in my copending application Ser. No. 757,031 filed Dec. 19, 1924, at a slow speed in one direction or at a fast speed in a reverse direction without reversing the motor. In specifically considering the fast feed mechanism it will be noted that the pinion 154 (Fig. 9) meshes with a spur gear 155 suitably journaled within suitable bearings 156 carried by the frame section 8 and the gear 155 has secured thereto and rotatable therewith a spur pinion 157 which in turn meshes with a larger internal gear 158. The hub 159 of the gear 158 is herein also journaled on a suitable bearing sleeve 160 on a sleeve clutch member 161 keyed, as at 162, to a longitudinally disposed horizontal main feed driving or transmission shaft 163 journaled at its opposite ends in suitable bearings 164 and 165 carried within the frame section. Moreover, it will be noted that the member 161 carries a series of friction disks 166 which disks cooperate with a corresponding series of disks 167 carried by the sleeve of the internal gear. As shown, the sleeve on the internal gear is also provided with a plurality of radially located longitudinally extending slots 168 receiving radial fingers 169 on an interlocking member 170 keyed to the hub of a pinion 171 freely rotatable on the shaft 163. Between these fingers 169 are friction clutch operating fingers 172 carried by a cylindrical plane member 173 disposed coaxially with the hub of the gear 158. These fingers 172 extend longitudinally in contact with one set of the friction disks 166, 167. As shown, the rear end of the shaft 163 has secured thereto as by a key 174, a spur pinion 175 which meshes with a spur gear 176 journaled within suitable bearings 177 carried by the frame section 8. The spur gear 176 has secured thereto and rotatable therewith a spur pinion 178 which meshes with a

larger internal gear 179 keyed, as at 180, to a longitudinally extending horizontal two-part transmission shaft 181 disposed coaxially with the transmission shaft 163 and in turn suitably journaled at its forward end within a roller bearing 182 carried within a head member 183 and journaled at its rear end within longitudinally spaced ball bearings 184 disposed within a bracket 185 secured as by screws 186 to a gear housing member 187 suitably secured at its opposite ends to the angle frame members 17 and 18. The rear end of the shaft 181 has secured thereto as by a suitable key 188 a bevel gear 189. It will thus be noted that the rotation of the armature shaft 36 may be transmitted to the pinion 154, gear 155, pinion 157, internal gear 158, friction clutch disks 166, 167, clutch member 161, shaft 163, pinion 175, gear 176, pinion 178, internal gear 179, and the shaft 181 to the bevel gear 189 to rotate the latter at a predetermined high or fast speed whenever the clutch controlling member 173 is operated to connect the clutch. It will here further be evident that the speed of such feed may be lowered at will by slipping the friction disks 166, 167. Referring specifically to the slow or cutting feed it will be noted that when the clutch controlling member 173 is in inoperative position and the clutch is released power will still be transmitted through the interlocking member 170 to the pinion 171 which is freely rotatable on the shaft 163. This pinion in turn meshes with a gear 190 disposed coaxially with the gear 176 and this gear has secured thereto and rotatable therewith a pinion 191 which meshes with a spur gear 192 disposed coaxially with and rotatable on the shaft 163. This gear 192 has secured thereto a spur pinion 193 which meshes with a spur gear 194 disposed coaxially with the gear 190 and this gear drives a spur pinion 195 which meshes with an internal gear 196 substantially similar to the internal gear 158. The internal gear 196 also houses a friction clutch substantially similar to the clutch heretofore described in connection with the clutch disks 166, 167 and this clutch includes clutch disks 197, 198 certain of which are carried on a clutch member 199 keyed, as at 200, to the shaft 163, while others are carried by a sleeve formed on the internal gear 196 and a clutch retaining member 201 is provided keyed, as at 202, to the hub of the spur pinion 175 and this clutch member in this instance has no interlocking function and is only a disk retaining member. A plane clutch operating member 203 surrounds the hub of the clutch member 201 and is provided with longitudinally extending fingers 204 which are adapted to engage one set of the friction disks 197, 198. As a result of this mechanism above described, although the clutch 166, 167 is disconnected, rotation will constantly be imparted through the pinion 171, gear 190, pinion 191, gear 192, pinion 193, gear 194, pinion 195, internal gear 196, clutch disks 197, 198, clutch member 199, pinion 175, gear 176, pinion 178, internal gear 179, and to the shaft 181 so that when the clutch 197, 198 is connected the bevel gear 189 will be rotated at a slow or cutting speed in an opposite or reverse direction from the fast speed previously described. Here it will also be evident that by slipping the friction disks 197, 198 this speed may also be reduced when desired.

Operatively associated with the feeding mechanism above described are pivoted clutch shipper members 205, 206 (see Fig. 6) provided at one end with suitable rollers 207 adapted to engage the plane surfaces of the clutch operating members 173 and 203, respectively. The outer ends of these shippers are also provided with rectangular portions 208 and 209 having arcuate engaging surfaces and these rectangular portions register with slots 210 and 211 formed in slidably engageable parallel rods 212 and 213, respectively (see Fig. 8) suitably guided within the machine frame at their opposite ends. These rods are provided at their rearward ends with semicircular portions having threads 214, 215 of opposite pitch and which are adapted to engage a two-part nut 216, each part having threads of opposite pitch which engage the threads on the members 212, 213. The nut 216 has secured thereto as by a transverse pin 217 a spur pinion 218 which is meshed with a larger internal gear 219 formed in a hand wheel 220 rotatably mounted, as at 221, upon a cylindrical bearing sleeve 222 carried by the bracket 185. It will be observed that rotation of the hand wheel 220 and consequently the threaded nut 216 engaging the threads formed on the rods 212, 213 will cause the latter to simultaneously move in opposite directions, thus causing one of the friction mechanisms to be released while the other is applied, thereby preventing simultaneous application of two speeds, i. e. the fast and slow speeds. As illustrated, the bevel gear 189 is meshed with reverse bevels 223, 224 freely rotatable upon bearing sleeves 225 carried by a transversely disposed truck driving shaft 226. The hubs of the gears 223 and 224 are disposed adjacent one another and have formed thereon gear clutch teeth 227, 228 adapted to be selectively connected by an internal shipper gear 229 with a spur gear 230 suitably secured to the shaft 226. A shipper yoke 231 engages the gear clutch member 229 and is secured to a vertical shaft 232 suitably journaled on the gear housing 187. This shaft has secured thereto at its upper end an operating lever 233. It will thus be evident that by selectively throwing the shipper gear in opposite directions into operative engagement with either of the gears 223 or 224 the shaft 226 will be driven in opposite directions by the gear 189.

at either a fast or a slow speed. The shaft 226 is journaled within the bracket 187 within suitable ball bearings 234 disposed adjacent the gears 223, 224, respectively, and in suitable roller bearings 235 disposed adjacent its ends and one end of this shaft has secured thereto as by a bolt and washer connection 236 a large sprocket 237. The sprocket 237 is connected by a chain connection 238 with a sprocket 239 secured to a transversely disposed shaft 240 disposed coaxially with the sleeves 24 and journaled in coaxial roller bearings 241 adjacent its ends suitably carried in bores 242 formed in the supporting arm 26. The end of the shaft 240 opposite from the sprocket 239 has secured thereto, as by a bolt and washer and key connection 243, a sprocket 244 which is connected through a chain connection 245 with a sprocket 246 suitably secured to a shaft 247 disposed parallel with the shaft 240. The shafts 240 and 247 are connected in operative driving relation with the truck wheels 31 carried by the axles 28 and 29, respectively, by gears 248 keyed to the shafts, as at 249, and which mesh with intermediate idler gears 250 freely rotatable upon a bearing sleeve 251 carried by studs 252 suitably carried by the arms 25 and 26, respectively. These intermediate gears 250 are meshed with spur gears 253 keyed, as at 254, to the axles 28 and 29, respectively. From the foregoing description it will be evident that the truck wheels 31 may be driven from the gear 189 at either a fast or a slow speed in opposite directions at the will of the operator. As illustrated, the truck driving shaft 226 has secured thereto, as by a key 255, an annular sleeve 256 which, in turn, has keyed thereto a brake member 257 having a peripheral groove 258 with which a brake band 259 is adapted to cooperate. The brake band 259 is provided with a suitable operating lever 260 disposed at the side of the machine frame (see Fig. 2). This brake is adapted to control the rotation of the shaft 226 during certain operations of the machine and for controlling truck movement while moving relative to a trackway of a steep gradient in a well known manner.

Associated with the machine propulsion mechanism is improved mechanism for bodily rotating the machine frame 5 and consequently the cutter bar 83 about the bearing surfaces 11 formed within the spacing or bearing members 9 and 10. Slidably mounted upon the shaft 181 in non-rotatable relation therewith is a gear 261 keyed, as at 262, to the shaft and provided at its rear end 263 with a flanged portion 263 with which a shipper yoke 264 cooperates. The yoke 264 is secured to a shaft 265 and has secured thereto at one end a suitable controlling lever 266. This sliding gear 261 is adapted to connect a larger spur gear 267 in operative driving re-

lation with the transmission shaft 181 and this gear 267 meshes with an arcuate rack 268 formed on a bracket 269 secured, as by bolts 270 to the angle members 17 and 18. It will thus be evident that when the gear 267 is connected in driving relation with the shaft 181 by the sliding gear 261 power will be transmitted selectively through the fast or slow feeding mechanism, thus causing the gear 267 to react upon the rack 268 and bodily rotating the machine in a vertical plane as indicated by dotted lines in Fig. 13 or in any intermediate plane, thus enabling the bar to be swung from the horizontal position shown in Figs. 1 and 2 to a vertical position, enabling the machine to operate as either a vertical or a horizontal cutter.

Improved means are provided for raising and lowering the machine frame to different vertically disposed horizontal planes and such means comprises worm gear segments 271 and 272 secured, as by bolts 273 (Fig. 12) to arms 274 and 275 secured to the parallel arms 25 and 26, respectively, and these gear segments are meshed with screw threaded portions 276 and 277, respectively, having threads of opposite lead which are formed upon a longitudinally disposed slidable shaft 278 suitably mounted at its ends within members 279 and 280 suitably carried by the angle member 18. The rear end of this shaft 278 is provided with vertically disposed circumferentially extending rack teeth 281 which mesh with a gear 282 (see Figs. 6 and 11) journaled upon a bearing sleeve 283 carried by the transverse shaft 226. This gear 282 is provided with a sleeve portion having gear teeth 284 formed thereon which are adapted to be connected to gear teeth 285 formed upon the sleeve 256 keyed to the shaft by means of an internal shipper gear 286. The shipper gear 286 is adapted to be actuated by means of a shipper yoke 287 secured to a vertical shaft 288 which has secured thereto, at its upper end, an actuating lever 289 (see Fig. 1). It will thus be evident that when the shaft 226 is connected in driving relation with the motor 35 and when the gear teeth 284 are connected in operative driving relation the gear 282 will be rotated thus causing the teeth thereon to react on the rack teeth 281 forcing the shaft 278 forwardly, thus causing the gear segments 271 and 272 to swing about the shafts 240 and 247 as pivots and causing the arms 25 and 26 to swing about the wheel carrying axles 28 and 29 and thus varying the elevation of the machine frame and cutter bar as desired, as indicated by dotted lines in Fig. 11.

Associated with the elevating mechanism is improved means for tilting the cutter bar, which means comprises a plurality of circumferentially longitudinally spaced apertures 290 in shaft 278 within which a suit-

- able lever or wrench, not shown, is adapted to be inserted, thereby enabling the operator to bodily rotate the shaft 278, thus causing the oppositely threaded screw portions 276 and 277 to swing the gear segments 271, 272 in opposite directions, tilting the machine frame as indicated by dotted lines in Fig. 11, the clutch member 286 controlling the gear 282 being thrown out at this time.
- 5 10 A friction clamping device (Fig. 7) generally designated 291, is provided, preventing rotation of the shaft 278 after the tilting operation is completed and this clamping device comprises a split clamp 292 secured, as by screws 293, to the angle member 18 and the clamp 292 is adapted to be operated by a bolt 294 pivoted thereto, as at 295, and having at its opposite end a screw and nut connection 296 for applying pressure to the clamp. It will also be noted that suitable sleeves 297 are provided for housing the shaft 278 thereby preventing access of any foreign substance to the worms 276 and 277 or rack 281.
- 15 20 25 Improved means is provided for counter-balancing the machine frame during the elevating and bar tilting operations and this means comprises a plurality of heavy coiled springs 298, herein four, carried by suitable sleeves surrounding the shafts 240 and 247, each of these springs having one end 299 reacting as at 300, Fig. 3, upon a lower portion of the spacing or bearing members 9 and 10, respectively, and the other end 301 engaging, as at 302, a portion of the parallel arms 25 and 26 carrying the wheeled axles 28 and 29, respectively. These springs relieve the load on the teeth formed on the shaft 278 and permit a smoother adjusting operation 30 35 40 of the bar and machine frame.
- 45 50 55 As illustrated, electric current is adapted to be conducted to the electric driving motor 35 through suitable conductor cables 303, 304 the former of which is connected to a suitable connector plug 305 of usual form carried by the machine frame and to the usual terminal plugs, a suitable fuse box being interposed adjacent the ends of the cable, while the latter conductor cable 304 is connected to a suitable cable reel 306 journaled, as at 307, upon a bracket member 308 suitably bolted to the angle members 17 and 18. The cable reel 306 is adapted to be driven from the truck driving shaft 226 by means of a suitable grooved pulley 309 suitably secured to a sleeve 310 keyed to the shaft and a belt 311 cooperates with this pulley and with a pulley 312 suitably secured to and rotatable with the reel, thus enabling the reel 60 65 to be driven by truck movement at any speed thereof. An adjustable idler pulley 313 is rotatably mounted upon a stud 314 secured to a pivoted bracket 315. The bracket 315 (Fig. 16) is in turn secured to a transversely disposed horizontal shaft 316 provided at its
- opposite end with an operating lever 317 disposed adjacent the side of the machine. A spring pressed plunger 318 is provided which is adapted to cooperate with teeth formed on a ratchet member 319 thereby holding the lever in any adjusted position. As illustrated, a tension spring 320 is provided having one end secured to a portion of the bracket 187 and its other end secured to a collar 321, the latter being held in rigid relation to the shaft 316 by means of a set screw 322. This spring constantly tends to hold the idler pulley 313 in its raised or inoperative position. It will thus be evident that the operator may vary the tension upon the belt 311 as desired consequently varying the speed of rotation of the reel. Suitable angularly disposed guiding rolls 323 are provided at the rear of the reel 306 for guiding the cable 304 as it is wound in or paid out by the reel. It will herein be noted that an operating handle 324 is provided at the rear end of the machine frame for actuating a suitable controlling mechanism (not shown) which controls the flow of electric current to the driving motor 35.

thrown out the gear 282 may be manually actuated causing the shaft 287 to slide longitudinally, swinging the arms 25 and 26 and thus varying the elevation of the machine frame.

The general mode of operation of the machine will now be described. It will be assumed that the machine is running about the mine along tracks in the entry at a fast or transport speed under the control of the friction clutch 166, 167 and when the working face of the coal is reached the fast feed clutch is then released. If an undercut is desired to be made the clutch 53 is connected and the operator then manipulates the hand wheel 140 controlling the fast bar swinging friction and the bar is swung or slued at a fast feed to a point adjacent the right hand rib. The clutch member 96 is thrown into operative driving relation and the cutter chain sprocket is then actuated through transmission means from the motor. The fast feed friction is then released and the slow feed clutch 197, 198 is thrown in and the bar dumped or fed into the coal at a slow or cutting speed, the friction elements 142 preventing rotation of the bar swinging worm 121 and locking the bar in position at this time. When the dumping cut is completed the slow truck feed clutch is then thrown out and the brake band 259 set, thus preventing rotation of the truck wheels and the hand wheel 119 is then manipulated causing application of the slow speed clutch 111 and the bar is consequently swung about its pivot, the slow bar swinging clutch 111 thereafter being released. The band 259 controlling rotation of the truck wheels is then released and the operator throws the gear clutch element 229 into driving relation with the other reverse gear and the slow truck feed friction 166, 167 is applied and the bar withdrawn from the coal at a cutting speed, in a well known manner. If it is desired to make a shear or vertical cut the sliding gear member 261 is thrown into mesh with the gear 267 and the machine and cutter bar bodily swung into a vertical position about its pivot, the clamps 19 being released at this time. The clamps 19 are then again tightened, holding the machine frame in non-rotative position and the bar is then swung up at a fast feed to a point adjacent the mine roof and the bar dumped into the coal at a cutting speed and then swung downwardly to the bottom of the mine and the bar withdrawn from the coal in a manner substantially similar to that heretofore described in regard to the horizontal cut. If it is desired to vary the elevation of the bar and the machine frame the clutch element 286 is thrown in operative driving relation with the gear member 285 secured to the truck driving shaft 226 and the worm 282 is rotated, thus sliding the shaft 278 and swinging the racks 271, 272 and consequently the machine frame upwardly to

any elevation desired. If it is desired to tilt the bar the clutch member 286 is thrown out and a suitable bar or wrench is inserted into the apertures 290 in the shaft 278 and the shaft rotated, causing the worm racks 271, 272 to be swung in opposite directions thus varying the angle of the machine frame relative to the horizontal and consequently the angle of the cutter bar relative to the mine bottom. Other operations and advantages of my invention will be clearly apparent to those skilled in the art.

While I have in this application specifically described one form and two modifications thereof which my invention may assume in practice, it will be understood that these forms are used for purposes of illustration and that the invention may be modified and embodied in various other forms without departing from its spirit or the scope of the appended claims.

What I claim as new and desire to secure by Letters Patent is:

1. In a mining machine, in combination, supporting means, a motor having a casing 90 rotatably mounted on said supporting means, cutting means carried by said motor casing, and means driven by said motor for elevating said casing relative to said supporting means.

2. In a mining machine, in combination, supporting means, a motor having a casing 95 rotatably mounted on said supporting means about an axis coincident with the axis of motor rotation, mechanism driven by said motor for rotating said casing, cutting means carried by said motor casing, and means for bodily elevating said casing and to vary the angle of said casing relative to said supporting means, said elevating and angling 100 means including means for tilting said motor casing about a transverse axis.

3. In a mining machine, in combination, supporting means, a motor having a casing 105 rotatably mounted on said supporting means about an axis coincident with the axis of motor rotation, cutting means carried by said motor casing, and means to vary the elevation of said casing and its angle relative to said supporting means including mechanism driven by said motor.

4. In a mining machine, a wheeled supporting frame, a machine frame rotatably mounted thereon for movement about a substantially horizontal axis and carrying a 110 driving motor and variable speed transmission mechanism driven thereby, cutting mechanism carried by said machine frame including a plane cutter bar, said cutting mechanism being rotatable with said machine frame to enable said cutter bar to operate in either a horizontal or a vertical plane, and means driven through said transmission mechanism for propelling said wheeled supporting frame from said motor. 115 120 125 130

5. In a mining machine, a wheeled supporting frame, a machine frame rotatably mounted thereon for movement about a substantially horizontal axis and carrying a driving motor and variable speed transmission mechanism driven thereby, cutting mechanism carried by said machine frame including a plane cutter bar, said cutting mechanism being rotatable with said machine frame to enable said cutter bar to operate in either a horizontal or a vertical plane, and means driven through said transmission mechanism for propelling said wheeled supporting frame from said motor irrespective of the position of said motor relative thereto. 10
6. In a mining machine, a wheeled supporting frame, a machine frame rotatably mounted thereon for movement about a substantially horizontal axis and carrying a driving motor and variable speed transmission mechanism driven thereby, cutting mechanism carried by said machine frame including a plane cutter bar, said cutting mechanism being rotatable with said machine frame to enable said cutter bar to operate in either a horizontal or a vertical plane, and means driven through said transmission mechanism for driving the support wheels from said motor irrespective of the position of said motor relative thereto. 20
7. In a mining machine, a truck, a motor thereon having a casing rotatable about an axis coincident with the axis of motor rotation, cutting mechanism driven by said motor and carried by said casing, and truck driving mechanism operatively connected to said motor including transmission means having a casing secured to and rotatable with said motor casing and housing transmission mechanism including a plurality of friction clutches. 35
8. In a mining machine, a truck, a motor thereon having a casing rotatable about an axis coincident with the axis of motor rotation, cutting mechanism driven by said motor and carried by said casing, and truck driving mechanism operatively connected to said motor including transmission means having a casing secured to and rotatable with said motor casing and housing transmission mechanism including a plurality of friction clutches, and mechanism operatively connectible to said truck driving mechanism for effecting rotation of said motor casing. 50
9. In a mining machine, a wheeled truck, a motor thereon having a casing rotatable about an axis coincident with the axis of motor rotation, cutting mechanism driven by said motor, means for bodily elevating said motor casing relative to the truck wheels, and truck driving mechanism operatively connectible to said motor. 60
10. In a mining machine, a wheeled truck, a motor thereon having a casing rotatable about an axis coincident with the axis of motor rotation, cutting mechanism driven by said motor, means for bodily elevating said motor casing relative to the truck wheels through driving mechanism operatively connectible to said motor, and mechanism operatively connectible to said truck driving mechanism for effecting rotation of said motor casing. 70
11. In a mining machine, a wheeled truck, a motor thereon having a casing rotatable about an axis coincident with the axis of motor rotation, cutting mechanism driven by said motor, means for bodily elevating said casing relative to the truck wheels, and truck driving mechanism operatively connectible to said motor irrespective of the position of said motor casing relative to the truck wheels. 75
12. In a mining machine, in combination, a motor, a support rectilinearly movable towards and from a working face during the cutting operation of the machine, a motor casing in which said motor is disposed rotatably mounted on said support for rotation about an axis parallel to the direction of rectilinear movement of said support during cutting, means driven by said motor for elevating said casing, and cutting mechanism carried by said casing and rotatable therewith. 80
13. In a mining machine, a wheeled support, a motor casing rotatably mounted on said support for movement about a substantially horizontal axis coincident to the axis of motor rotation, cutting mechanism carried by said casing, driving connections between said motor and the wheels of said support for propelling the latter, and means for bodily elevating said casing relative to the support wheels. 90
14. In a mining machine, a wheeled support, a motor having a casing rotatably mounted for movement about its longitudinal axis on said support, means on said support engaging said casing for locking the latter against rotation, cutting mechanism carried by said casing including a cutter bar, driving connections between said motor and the wheels of said support for propelling the latter, and means for changing the angle of said casing relative to the support wheels to tilt said cutter bar. 100
15. In a mining machine, a wheeled support, a motor having a casing rotatably mounted for movement about its longitudinal axis on said support, cutting mechanism carried by said casing, driving connections between said motor and the wheels of said support for propelling the latter, and means for angling and bodily elevating said casing relative to the wheels of said support. 110
16. In a mining machine, in combination, supporting means, a motor having a rotatable power shaft, a motor casing enclosing said motor and mounted on said supporting means. 115

- for rotation about an axis coincident with the axis of said shaft, a cutter carried by said casing, and means driven by said motor to bodily elevate said casing relative to said supporting means. 5 a casing housing said motor rotatable about the axis thereof, cutting mechanism carried by said casing, and means for rotating said casing including a plurality of friction clutches and a sliding clutch. 70
17. In a mining machine, in combination, supporting means, a motor having a rotatable power shaft, a motor casing enclosing said motor and mounted on said support for 10 rotation about an axis coincident with the axis of said shaft, a cutter carried by said casing, and means to angle and bodily elevate said cutter relative to said supporting means, said means including mechanism driven by 15 said motor. 24. In a mining machine, a driving motor, a casing housing said motor rotatable about the axis thereof, cutting mechanism carried by said casing, and means for rotating said casing including a plurality of friction 75 clutches disposed coaxially with the axis of rotation thereof. 25. In a mining machine, a driving motor, a casing housing said motor rotatable about the axis thereof, cutting mechanism carried by said casing and means for rotating said casing including an arcuate rack and gearing cooperating therewith, and a plurality of friction clutches controlling said gearing. 80
18. In a mining machine, in combination, supporting means, a motor having a rotatable power shaft, a machine body including a motor casing enclosing said motor and 20 mounted on said supporting means for rotation about an axis coincident with the axis of said shaft, means driven by said motor including transmission mechanism housed within said rotatable machine body for effecting rotation of said casing, a cutter carried by said casing, and means to angle said casing relative to said supporting means. 25 26. In a mining machine, driving motor having a housing rotatable about the axis thereof, cutting mechanism carried by said housing, and means for rotating said housing at a plurality of speeds including a plurality of selectively operable friction clutches disposed coaxially with the axis of said motor. 85
19. In a mining machine, a driving motor, cutting mechanism driven by said motor including a pivoted cutter bar, and means for 30 swinging said cutter bar in opposite directions at different speeds including a clutch coaxial with the axis of said motor and a plurality of selectively operable speed controlling friction clutches and means for controlling said several clutches. 27. In a mining machine, a support having truck wheels, a cutter carrying frame mounted thereon, and means for varying the elevation of said frame relative to said truck 90 wheels including parallel arms pivoted on axes coincident with the wheel axes, and means for simultaneously moving said arms. 28. In a mining machine, a support, a cutter carrying frame mounted thereon, and means for adjusting said frame into different elevated positions including a plurality of gear segments and axially movable screws cooperating therewith. 100
20. In a mining machine, a driving motor, and cutting mechanism driven thereby including transmission gearing and a drive 35 sprocket, and a plurality of independently operable sliding clutches, one of said clutches being adapted to connect said gearing to said motor while the other clutch is adapted to connect said drive sprocket with said gearing. 40 29. In a mining machine, a support, a cutter carrying frame mounted thereon, and means for adjusting said frame into different elevated positions including parallel arms, gear segments fixed thereon, and axially movable screws cooperating with said gear segments. 105
21. In a mining machine, a driving motor, and cutting mechanism driven thereby including transmission gearing and a driven 45 sprocket, and a plurality of independently operable sliding clutches, one of said clutches being adapted to connect said gearing to said motor while the other clutch is adapted to connect said drive sprocket with said gearing, one of said clutches being disposed coaxially with the axis of said motor. 50 30. In a mining machine, a support, a cutter carrying frame mounted thereon, means for adjusting said frame into different elevated positions including parallel arms, gear segments fixed thereon, reciprocable screws cooperative with said gear segments, and means for simultaneously reciprocating said screws. 115
22. In a mining machine, a driving motor, and cutting mechanism driven thereby including transmission gearing and a drive 55 sprocket, and a plurality of independently operable sliding clutches, one of said clutches being adapted to connect said gearing to said motor while the other clutch is adapted to connect said drive sprocket with said gearing, one of said clutches being disposed coaxially with said sprocket. 60 31. In a mining machine, supporting 120 means, a cutter carrying frame mounted thereon, and means for varying the angle in altitude of said frame relative to said supporting means including a plurality of oppositely movable front and rear supporting arms, and means including a mechanical connection between said arms for simultaneously moving said arms in the same direction. 125
23. In a mining machine, a driving motor, 65 32. In a mining machine, supporting 125

means, a cutter carrying frame mounted thereon, and means for varying the angle in altitude of said frame relative to said supporting means including a plurality of oppositely movable gear segments, and a screw threaded member cooperating therewith for moving said gear segments simultaneously or independently.

33. In a mining machine, supporting means, a cutter carrying frame mounted thereon, means for varying the angle in altitude of said frame relative to said supporting means including a plurality of oppositely movable gear segments, and means for causing simultaneous movement of said gear segments in the same direction comprising a screw threaded member cooperating therewith.

34. In a mining machine, supporting means, a cutter carrying frame mounted thereon, means for varying the angle in altitude of said frame relative to said supporting means including a plurality of gear segments cooperating therewith having teeth of opposite pitch, and means for causing simultaneous movement of said gear segments in the same direction.

35. In a mining machine, supporting means, a cutter carrying frame movably mounted thereon, constantly acting resilient means between said frame and said supporting means constantly tending to move said frame relative to said supporting means, and means for positively moving said frame against the action of said resilient means.

36. In a mining machine, supporting means, a cutter carrying frame movably mounted thereon, constantly acting resilient counterbalancing means between said frame and said supporting means constantly tending to move said frame relative to said supporting means, and means for positively moving said frame against the action of said resilient means.

37. In a mining machine, supporting means, a cutter carrying frame mounted thereon, and means to elevate or to change the angle in altitude of said frame relative to said supporting means including a reversely threaded screw, and means for selectively rotating or reciprocating said screw.

38. In a mining machine, a wheeled support, a machine frame rotatably mounted thereon carrying a driving motor and variable speed transmission mechanism, cutting mechanism including a cutter head supported by and rotatable with said frame, said cutting mechanism being positionable to cut in horizontal or vertical planes by rotation of said frame, and means for driving the wheels of said truck in opposite directions from said transmission mechanism including reverse gearing.

39. In a mining machine, a support, a machine frame mounted thereon and rotatable

relative thereto about its longitudinal axis, cutting mechanism carried by said frame, and means including a plurality of pivoted clamps to maintain said frame in non-rotative relation relative to said support.

40. In a mining machine, a machine frame, cutting mechanism carried thereby, means for elevating said cutting mechanism including parallel arms pivoted on said frame and truck wheels carried by said arms, said arms being also pivoted on axes coincident with the wheel axes, and means for swinging said arms while their parallel relation is substantially maintained.

41. In a mining machine, a machine frame, kerf cutting mechanism carried thereby, and means for elevating said cutting mechanism including a plurality of parallel arms pivoted on said frame, wheeled axles carried by said arms, and transmission means between the pivotal axes of said arms and said axles.

42. In a mining machine, a machine frame, kerf cutting mechanism carried thereby, a driving motor and variable speed transmission mechanism carried by said frame, means for elevating said cutting mechanism including a plurality of parallel arms pivoted on said frame, wheeled axles carried by said arms, and operative driving connections between said transmission mechanism and said axles.

43. In a mining machine, a machine frame, kerf cutting mechanism carried thereby, a driving motor carried by said machine frame, means for elevating said frame including a plurality of parallel arms, wheeled axles carried by said arms, and means for driving said wheeled axles from said motor irrespective of the elevation of said frame.

44. In a mining machine, a wheeled support, a driving motor, a casing housing said motor rotatable about the axis thereof, cutting mechanism including a cutter head rotatable with said casing, and means for driving the wheels of said support from said motor including a transverse shaft and a clutch disposed coaxially therewith.

45. In a mining machine, cutting mechanism, a driving motor, a feeding mechanism driven by said motor for effecting feeding movement of said cutting mechanism including a plurality of friction clutches, and means for selectively operating said clutches including a member rotatable about the axis of said motor.

46. In a mining machine, a wheeled support, a machine casing rotatably mounted thereon including a driving motor, cutting mechanism including a cutter head rotatable with said casing, and means for rotating said casing relative to said support including a clutch disposed coaxially with the axis thereof.

47. In a mining machine, a wheeled support, a machine casing mounted thereon, cut-

- ting mechanism carried by said casing, a motor for driving said cutting mechanism, and means driven by said motor for bodily elevating said cutting mechanism relative to the support wheels to position the same in 5 differently elevated parallel positions including a reciprocable shaft, and means for maintaining said shaft in a stationary position relative to said support.
48. In a mining machine, a wheeled support, a machine casing mounted thereon, cutting mechanism carried by said casing, a motor for driving said cutting mechanism, means driven by said motor for bodily elevating said cutting mechanism relative to the support wheels including a reciprocable shaft, and means for frictionally clamping said shaft in stationary position relative to said support.
49. In a mining machine, a body including cutting mechanism, and vertically adjustable supporting means therefor comprising spaced arms pivoted between their ends and having wheels at one side of their pivots, 10 an axially adjustable shaft mounted on the body and movably connected to the arms at the other side of their pivots, and means for adjusting said shaft.
50. In a mining machine, a body including cutting mechanism, and vertically adjustable supporting means therefor comprising spaced pivoted arms, wheels on said arms, arcuate racks on said arms, an axially movable shaft mounted on the body and having 15 oppositely threaded portions in mesh with said racks, and means for rotating said shaft and for moving it axially.
51. In a mining machine, a body including cutting mechanism, and vertically adjustable supporting means therefor comprising spaced pivoted arms, wheels on said arms, arcuate racks on said arms, an axially movable shaft mounted on said body and having 20 portions in mesh with said racks, and means for adjusting said shaft axially.
52. In a mining machine, a body including cutting mechanism, pivoted arms on said body carrying supporting wheels, a motor in said body, a counter shaft mounted on said body and having a reversible driving connection with said motor, a driving connection between said shaft and the wheels, arcuate racks on said pivoted arms, a longitudinally extending axially movable shaft mounted on 25 said body and having portions in mesh with said racks, and means for imparting axial movement to said longitudinally extending shaft by power from said counter shaft.
53. In a mining machine, the combination 30 of a truck supported body, a head overhanging one end of the truck and carrying a pivotally mounted cutter bar, a motor in said body, a driving connection between the motor and the truck wheels, and driving connections between said motor and the cutter
- bar for imparting angular movement thereto including separate clutches controlling opposite movements of the cutter bar, and means cooperating with the bar angling means for restraining said bar from movement when both said clutches are released. 70
54. In a mining machine, the combination of a truck supported body, a head overhanging one end of the truck and carrying a pivotally mounted cutter bar, a motor in said body, a driving connection between the motor and truck wheels, and driving connections between said motor and the cutter bar for imparting angular movement thereto including a driven shaft in geared relation to said cutter bar, separate clutches controlling opposite driving connections to said shaft, and means cooperating with the bar angling means for preventing movement thereof under weight of the cutter bar when both said clutches are released. 75
55. In a mining machine, supporting means, a cutter carrying frame mounted thereon, and means for varying the angle in altitude of said frame relative to said supporting means including a pair of arcuate toothed members, and an axially movable reversely threaded screw cooperating therewith. 80
56. In a mining machine, supporting means, a cutter carrying frame mounted thereon, and means for varying the angle in altitude of said frame relative to said supporting means including a pair of arcuate toothed members, a reversely threaded screw 85 cooperating therewith, and means for moving said screw axially or angularly. 100
57. In a mining machine, supporting means, a cutter carrying frame mounted thereon, and means for varying the angle in altitude of said frame relative to said supporting means including a pair of arcuate toothed members movable in the same direction, a reversely threaded screw cooperating therewith, and means for rotating said screw. 105
58. In a mining machine, supporting means, a cutter carrying frame mounted thereon, a motor carried by said frame, and means driven by said motor for varying the elevation of said frame relative to said supporting means including a pair of arcuate toothed members, and a reversely threaded screw 110 cooperating therewith.
59. In a mining machine, supporting means, a cutter carrying frame mounted thereon, a motor carried by said frame, and means for varying the angle in altitude of said frame relative to said supporting means including a pair of arcuate toothed members, a reversely threaded screw cooperating therewith, and means driven by said motor for moving said screw axially. 115
60. In a mining machine, supporting means, a cutter carrying frame mounted thereon, and means for varying both the 120
- 125
- 130

- angle in altitude or elevation of said frame relative to said supporting means including a pair of arcuate toothed members, and a reversely threaded screw cooperating therewith. 5
61. In a mining machine, supporting means, a cutter carrying frame mounted thereon, and means for varying both the angle in altitude or elevation of said frame relative to said supporting means including a pair of arcuate toothed members, a reversely threaded screw cooperating therewith, and means for moving said screw axially. 10
62. In a mining machine, supporting means, a cutter carrying frame mounted thereon, and means for varying the angle in altitude or elevation of said frame relative to said supporting means including a pair of arcuate toothed members, a reversely threaded screw cooperating therewith, and means for moving said screw axially. 15
63. In a mining machine, a driving motor, cutting mechanism driven thereby including a pivoted cutter bar and a cutter chain drive sprocket, bar swinging mechanism including transmission gearing driven by said motor, and a plurality of independently operable sliding clutches, one of said clutches being adapted to connect said transmission gearing to said motor for drive by the latter while the other clutch is adapted to connect said cutter chain drive sprocket to said gearing for drive by said gearing. 20
64. In a mining machine, a driving motor, cutting mechanism driven thereby including a pivoted cutter bar and a cutter chain drive sprocket, bar swinging mechanism including transmission gearing driven by said motor, and a plurality of independently operable sliding clutches, one of said clutches being adapted to connect said transmission gearing to said motor for drive by the latter while the other clutch is adapted to connect said cutter chain drive sprocket to said gearing for drive by said gearing, one of said clutches being disposed coaxially with the axis of said motor. 25
65. In a mining machine, a driving motor, cutting mechanism driven thereby including a pivoted cutter bar and a cutter chain drive sprocket, bar swinging mechanism including transmission gearing driven by said motor, and a plurality of independently operable sliding clutches, one of said clutches being adapted to connect said transmission gearing to said motor for drive by the latter while the other clutch is adapted to connect said cutter chain drive sprocket to said gearing for drive by said gearing, one of said clutches being disposed coaxially with said sprocket. 30
66. In a mining machine, a horizontal motor having a casing rotatable about an axis coincident with the axis of motor rotation, cutting mechanism carried by said casing, a frame carried by and rotatable with
- said motor casing, and means carried by said rotatable frame and driven by said motor for effecting rotation of said casing at different speeds including a plurality of selectively operable speed controlling clutches. 70
67. In a mining machine, a horizontal motor having a casing rotatable about the axis of rotation of said motor, cutting mechanism carried by said rotatable casing, and means driven by said motor for rotating said casing at different speeds including a plurality of selectively operable speed controlling clutches, and a sliding clutch. 75
68. In a mining machine, a horizontal driving motor, a casing housing said motor rotatable about the axis thereof, cutting mechanism carried by said rotatable casing, and means driven by said motor for rotating said casing at different speeds including a plurality of selectively operable speed controlling clutches disposed coaxially with the axis of rotation thereof. 80
69. In a mining machine, a horizontal driving motor, a casing housing said motor rotatable about the axis thereof, cutting mechanism carried by said casing, a frame carried by and rotatable with said casing, and means driven by said motor for rotating said casing at different speeds including an arcuate rack and gearing cooperating therewith, and a plurality of selectively operable speed controlling clutches controlling said gearing, said gearing and clutches being housed within said rotatable casing. 85
70. In a mining machine, a wheeled truck, a motor thereon having a casing rotatable about the axis of said motor, cutting mechanism carried by said rotatable casing, means driven by said motor for bodily elevating said casing relative to the truck wheels, and truck driving mechanism operatively connected to said motor. 90
71. In a mining machine, a wheeled truck, a motor thereon having a casing rotatable about the axis of said motor, cutting mechanism carried by said rotatable casing, means driven by said motor for bodily elevating said casing relative to the truck wheels, truck driving mechanism operatively connectible to said motor, and casing rotating mechanism on said truck operatively connectible to said truck driving mechanism. 95
72. In a mining machine, a wheeled truck, a motor thereon having a casing rotatable about the axis of said motor, cutting mechanism carried by said rotatable casing, means driven by said motor for bodily elevating said casing relative to the truck wheels, and truck driving mechanism operatively connectible to said motor irrespective of the position of said casing. 100
73. In a mining machine, a wheeled truck, a motor thereon having a casing rotatable about the axis of said motor, cutting mechanism carried by said rotatable casing, means 105

driven by said motor for bodily, elevating said casing relative to the truck wheels, truck driving mechanism operatively connectible to said motor, and means for rotating said casing including mechanism driven by said motor.

74. In a mining machine, supporting means, a motor having a casing rotatably mounted thereon, cutting mechanism carried by said rotatable casing and positioned for cutting in different planes by rotation of said casing, means driven by said motor for rotating said casing, and means for locking said casing in a stationary position relative to said supporting means.

75. In a mining machine, a support, a machine frame rotatably mounted thereon, cutting mechanism supported by said rotatable frame, a motor having its axis horizontally disposed and extending longitudinally of the machine, means driven by said motor for rotating said frame, and means to clamp said frame through friction only against rotation relative to said support.

76. In a mining machine, a support, a machine frame mounted thereon and rotatable relative thereto, cutting mechanism supported by said rotatable frame, a motor, means driven by said motor for rotating said frame, and means to clamp said frame in non-rotative relation relative to said support including a plurality of separate pivoted clamps.

77. In a mining machine, a wheeled support, a driving motor having a casing rotatably mounted about the longitudinal axis thereof on said support, cutting mechanism including, a cutter head rotatable with said casing, a frame secured to and rotatable with said casing, means driven by said motor for rotating said casing, and means including transmission mechanism housed in said rotatable frame and for driving the wheels of said support.

78. In a mining machine, cutting mechanism including a pivoted cutter bar, means for swinging said cutter bar about its pivot including a controlling clutch, and separate frictional means cooperating with said bar swinging means for preventing swinging of said bar under the weight thereof when said clutch is released.

79. In a mining machine, cutting mechanism including a pivoted cutter bar, means for swinging said cutter bar about its pivot including a controlling clutch, and separate means including a frictional device for preventing swinging of said bar under the weight thereof when said clutch is released.

80. In a mining machine, a body, cutting mechanism carried thereby, and adjustable supporting means for varying the elevation of said body comprising spaced front and rear arms pivoted between their ends at oppo-

site sides of said body and having wheels at one side of their pivots, adjusting means mounted on said body for effecting swinging movement of said arms including a mechanical connection extending between said arms at one side of said body and movably connected to the arms at the other side of their pivots, and means for actuating said adjusting means to effect simultaneous swinging movement of all of said arms.

81. In a mining machine, a body, cutting mechanism carried thereby, and adjustable supporting means for said body for varying the elevation thereof and comprising spaced front and rear arms pivoted between their ends at opposite sides of said body and having wheels at one side of their pivots and toothed elements at the other side of their pivots, adjusting means mounted on said body for effecting swinging movement of said arms including a mechanical connection extending between said arms at one side of said body and having toothed portions movably connected to said toothed elements, and means for actuating the toothed portions of said adjusting means to effect simultaneous swinging movement of all of said arms.

82. In a mining machine, a body, cutting mechanism carried thereby, and adjustable supporting means for said body for varying the elevation thereof comprising spaced arms pivoted between their ends, said arms having wheels at one side of their pivots and arcuate toothed racks at the other side of their pivots, adjusting means mounted on said body for effecting swinging movement of said arms including a mechanical connection between said arms and having toothed portions meshing with said arcuate racks, and means for actuating the toothed portions of said adjusting means.

83. In a mining machine, a body carrying a motor, cutting mechanism carried by said body, means for adjustably supporting said body to vary its elevation comprising spaced front and rear parallel arms pivoted between their ends and having wheels at one side of their pivots, means for effecting swinging movement of said arms while maintaining the latter in substantially parallel relation including adjusting mechanism mounted on said body and movably connected to said arms at the other side of their pivots, means for actuating said adjusting mechanism, and mechanism driven by said motor for driving the wheels of said supporting means irrespective of the elevation of said body relative to the support wheels.

84. In a mining machine, a body, cutting mechanism carried thereby, and adjustable supporting means for said body for varying the elevation thereof and comprising spaced front and rear parallel arms pivoted between their ends and having wheels at one side of their pivots and toothed elements at the other

side of their pivots, means for effecting swinging movement of said arms while maintaining the latter in substantially parallel relation including adjusting means mounted on said body and having toothed portions movably connected to said toothed elements, means for actuating the toothed portions of said adjusting means, and mechanism driven by said motor for driving the wheels of said supporting means irrespective of the elevation of said body relative to the support wheels.

85. In a mining machine, a body, cutting mechanism carried thereby, and adjustable supporting means for said body for varying the elevation thereof comprising spaced arms pivoted between their ends, said arms having wheels at one side of their pivots and arcuate toothed racks at the other side of their pivots, means for effecting swinging movement of said arms including adjusting means mounted on said body and having toothed portions meshing with said arcuate racks, means for actuating the toothed portions of said adjusting means, and mechanism driven by said motor for driving the wheels of said supporting means irrespective of the elevation of said body relative to the support wheels.

86. In a mining apparatus, a machine frame, cutting mechanism carried thereby, and mechanism for varying the elevation of said frame comprising a wheeled support having pivoted front and rear arms disposed at opposite sides of the apparatus and mechanism including a mechanical connection common to the swinging of all of said arms and extending between said arms at one side of said frame for effecting simultaneous swinging movement of said arms to elevate said frame.

87. In a mining apparatus, a machine frame, cutting mechanism carried thereby, a motor carried by said frame, and mechanism driven by said motor for varying the elevation of said frame and cutting mechanism comprising wheeled supporting means having pivoted front and rear arms and mechanism including a mechanical connection between said arms for effecting simultaneous swinging movement of said arms, the connection between said arms and said mechanical connection lying in a common vertical longitudinally extending plane.

88. In a mining machine, a frame, supporting means for said frame including adjustable front and rear supports, a motor mounted on said supports and having its casing rotatable relative to said frame about an axis coincident with the axis of motor rotation, cutting mechanism carried by said motor casing, mechanism driven by said motor for simultaneously adjusting said supports for varying the elevation of said body, and means permitting adjustment of one of said

supports relative to the other to change the angle in altitude of said body.

89. In a mining machine, a machine body rotatable about a substantially horizontal axis extending longitudinally of the machine, supporting means therefor including adjustable front and rear supports, cutting mechanism carried by said body, a motor, mechanism driven by said motor for simultaneously adjusting said supports to vary the elevation of said body, and means permitting adjustment of one of said supports relative to the other to change the angle of said body.

90. In a mining machine, a motor casing rotatable about a substantially horizontal axis extending longitudinally of the machine, supporting means therefor including adjustable front and rear supports, cutting mechanism including a cutter head carried by said casing, a motor in said casing, mechanism driven by said motor for simultaneously adjusting said supports to vary the elevation of said casing, and means permitting adjustment of one of said supports relative to the other to change the angle of said casing.

91. In a mining machine, a machine body, cutting mechanism carried thereby, a motor carried by said body and having its casing rotatable about an axis coincident with the axis of motor rotation, said cutting mechanism being rotatable with said casing, supporting means for said body including adjustable front and rear supports, and mechanism including elements driven by said motor for simultaneously adjusting said supports or for adjusting one of said supports relative to the other support.

92. In a mining machine, supporting means, a machine frame thereon rotatable about a substantially horizontal axis extending longitudinally of the machine, cutting mechanism carried by said frame including a pivoted cutter bar, a motor carried by said frame, and mechanism carried by said frame and driven by said motor for effecting rotation of said frame about its axis.

93. In a mining machine, supporting means, a machine frame thereon rotatable about a substantially horizontal axis extending longitudinally of the machine, cutting mechanism carried by said frame including a pivoted cutter bar, a motor carried by said frame, and mechanism carried by said frame and driven by said motor for effecting rotation of said frame about its axis including an arcuate toothed member coaxial with the axis of movement of said frame, and a gear meshing with said arcuate member.

94. In a mining machine, supporting means, a machine frame thereon rotatable about a substantially horizontal axis extending longitudinally of the machine, cutting mechanism carried by said frame including a pivoted cutter bar, a motor carried by said

- frame, and mechanism carried by said frame and driven by said motor for effecting rotation of said frame about its axis including an arcuate toothed member coaxial with the axis of movement of said frame, and a gear meshing with said arcuate member, said mechanism including means for effecting rotation of said gear in opposite directions to effect rotation of said frame in opposite directions.
95. In a mining machine, supporting means, a machine frame thereon rotatable about a substantially horizontal axis extending longitudinally of the machine, cutting mechanism carried by said frame including a pivoted cutter bar, a motor, and a plural speed mechanism carried by said frame and driven by said motor for effecting rotation of said frame about its axis including an arcuate toothed member coaxial with the axis of movement of said frame, and a gear meshing with said arcuate member, said mechanism including means for rotating said gear at a plurality of substantially different speeds.
96. In a mining machine, supporting means, a frame mounted thereon, cutting mechanism carried by said frame, and means for varying the elevation of said frame relative to said supporting means including a pair of arcuate toothed members, and adjusting means for said toothed members including axially movable toothed portions connected to said toothed members.
97. In a mining machine, in combination, supporting means, a frame thereon including a cutter carrying head rotatable about a substantially horizontal axis and a cutter bar pivotally connected to said head, a motor carried by said frame, means driven by said motor for rotating said cutter head relative to said supporting means, and mechanism driven by said motor for bodily elevating said frame relative to said supporting means.
98. In a mining machine, in combination, supporting means, a frame thereon including a cutter carrying head rotatable about a substantially horizontal axis and a cutter bar pivotally connected to said head, a motor carried by said frame, means driven by said motor for rotating said cutter head relative to said supporting means, and means for bodily elevating said frame and to vary the angle in altitude of said frame relative to said supporting means including means for tilting said frame about a substantially transverse axis.
99. In a mining machine, in combination, supporting means, a frame thereon including a cutter carrying head rotatable about a substantially horizontal axis and a cutter bar pivotally connected to said head, a motor carried by said frame, means driven by said motor for rotating said cutter head relative to said supporting means, and means to vary the elevation of said frame and its angle in altitude relative to said supporting means including mechanism driven by said motor.
100. In a mining machine, a wheeled supporting truck, a frame thereon including a cutter carrying head rotatable about a substantially horizontal axis extending longitudinally of the machine, a motor carried by said frame, means for bodily elevating said frame relative to the truck wheels permitting positioning of said frame in differently elevated parallel positions, and truck driving mechanism for driving the wheels of said truck operatively connectible to said motor.
101. In a mining machine, wheeled supporting means, a frame thereon including a cutter carrying head rotatable about a substantially horizontal axis extending longitudinally of the machine, a motor carried by said frame, means for bodily elevating said frame relative to the truck wheels permitting positioning of said frame in differently elevated parallel positions, truck driving mechanism for driving the wheels of said truck operatively connectible to said motor, and rotating mechanism for said cutter head on said truck operatively connectible to said truck driving mechanism.
102. In a mining machine, a body including cutting mechanism and vertically adjustable supporting means therefor comprising spaced front and rear arms pivoted between their ends and having wheels at one side of their pivots, aligned rotatable screw means mounted on said body and operatively connected to and extending between the arms at the other side of their pivots, and means for actuating said screw means.
103. In a mining machine, a body including cutting mechanism and vertically adjustable supporting means therefor, comprising spaced front and rear pivoted arms, wheels on said arms, arcuate racks on said arms, means mounted on said body and cooperating with and extending between said racks for swinging said arms including axially movable toothed portions, and means for adjusting said toothed portions axially.
104. In a mining machine, wheeled supporting means, a machine body thereon, a motor in said body having its power shaft disposed substantially horizontally and extending longitudinally of the machine, cutting mechanism carried by said body including a rotatable cutter head and a cutter chain carrying cutter bar pivoted thereon, said cutter chain being driven from the forward end of said motor, mechanism driven from the rear end of said motor for effecting rotation of said cutter head, mechanism driven from the rear end of said motor for varying the elevation of said body, and mechanism driven from the rear end of said motor for driving the wheels of said supporting means.
105. In a mining machine, wheeled sup-

porting means, a machine body thereon, a motor in said body having its power shaft disposed substantially horizontally and extending longitudinally of the machine, cutting mechanism carried by said body including a rotatable cutter head and a cutter chain carrying cutter bar pivoted thereon, said cutter chain being driven from the forward end of said motor, mechanism driven from the forward end of said motor for effecting swing movements of said cutter bar, mechanism driven from the rear end of said motor for effecting rotation of said cutter head, mechanism driven from the rear end of said motor for varying the elevation of said body, and mechanism driven from the rear end of said motor for driving the wheels of said supporting means.

106. In a mining machine, in combination, supporting means, a motor having a casing rotatably mounted on said supporting means about an axis coincident with the axis of motor rotation, mechanism for rotating said casing, cutting mechanism carried by said casing including a pivoted cutter bar swingable relative thereto, and means for bodily elevating said casing and for varying the angle in altitude of said casing relative to said supporting means including means for tilting said casing about a transverse axis.

107. In a mining machine, cutting mechanism including a pivoted cutter bar, means for swinging said cutter bar about its pivot including a controlling clutch, and constantly acting means independent of said swinging means for preventing swinging of said bar under the weight thereof when the said clutch is released.

108. In a mining machine, cutting mechanism including a pivoted cutter bar, and means for swinging said cutter bar about its pivot including a controlling clutch, and constantly acting means independent of said swinging means including a frictional device for restraining swinging of said bar under the weight thereof when said clutch is released.

109. In a mining machine, in combination, supporting means, a motor having a casing rotatably mounted on said supporting means for rotation about an axis coincident with the axis of motor rotation, cutting means carried by said motor casing, mechanism driven by said motor for effecting rotation of said motor casing relative to said supporting means, and mechanism driven by said motor for varying the elevation of said casing relative to said supporting means.

110. In a mining machine, in combination, adjustable wheeled supporting means adapted to run along the trackway including a frame, a body mounted on said frame for rotation about a substantially longitudinal axis, cutting mechanism carried by said body including a cutter bar carrying cutter head, a

motor carried by said body and rotatable therewith, mechanism driven by said motor for varying the elevation of said frame relative to the trackway, mechanism driven by said motor for actuating said cutting mechanism, and mechanism driven by said motor for effecting rotation of said body about its axis.

111. In a mining machine, a machine body rotatable about a substantially horizontal axis extending longitudinally of the machine, cutting mechanism including a cutter head carried by and rotatable with said body, a motor carried by said body, and adjustable supporting means for said body including adjustable front and rear supports, and mechanism for adjusting said supports including a mechanical connection extending between said supports and movably connected thereto, and means driven by said motor for actuating said mechanical connection.

112. In a mining machine, a machine body rotatable about a substantially horizontal axis extending longitudinally of the machine, cutting mechanism including a cutter head carried by and rotatable with said body, a motor carried by said body, and adjustable supporting means for varying the elevation of said body comprising spaced front and rear arms pivoted between their ends and having wheels at one side of their pivots, adjusting means for effecting swinging movement of said arms including a mechanical connection extending between said arms and movably connected to the arms at the other side of their pivots, and means driven by said motor for actuating said adjusting means.

113. In a mining machine, supporting means, a motor thereon having its casing rotatable about a substantially horizontal axis extending longitudinally of the machine, cutting mechanism including a cutter head carried by and rotatable with said body, a motor carried by said body, and adjustable supporting means for said body including adjustable front and rear supports, and mechanism for adjusting said supports including a mechanical connection extending between said supports and movably connected thereto, and means driven by said motor for actuating said mechanical connection.

114. In a mining machine, supporting means, a motor thereon having its casing rotatable about a substantially horizontal axis extending longitudinally of the machine, cutting mechanism including a cutter head supported by and rotatable with said casing, and adjustable supporting means for varying the elevation of said casing comprising spaced front and rear arms pivoted between their ends and having wheels at one side of their pivots, adjusting means for effecting swinging movement of said arms including a mechanical connection extending between said

arms and movably connected to the arms at the other side of their pivots, and means driven by said motor for actuating said adjusting means.

- 5 115. In a mining machine, a body, cutting mechanism carried thereby, and adjustable supporting means for said body for varying the elevation thereof and comprising spaced arms pivoted between their ends and having 10 wheels at one side of their pivots and toothed elements at the other side of their pivots, adjusting means mounted on said body for effecting swinging movement of said arms including a mechanical connection between said 15 arms and having alined toothed portions movably connected to said toothed elements, and means for actuating the toothed portions of said adjusting means.

116. In a mining machine, a body, cutting 20 mechanism carried thereby, a motor carried by said body, and adjustable supporting means for said body for varying the elevation thereof and comprising spaced arms pivoted between their ends and having wheels at 25 one side of their pivots and toothed elements at the other side of their pivots, means for effecting swinging movement of said arms including adjusting means mounted on said body and having alined toothed portions 30 movably connected to said toothed elements, means for actuating the toothed portions of said adjusting means, and mechanism driven by said motor for driving the wheels of said truck irrespective of the elevation of said body relative to the truck wheels.

117. In a mining machine, a portable support, a horizontal motor mounted thereon for rotation about an axis coincident with the axis of motor rotation, means for journaling said motor casing on said support including bearing means at opposite ends of said motor in axial alinement with the motor axis, and cutting mechanism driven by said motor including a rotatable cutter head having a reduced neck extending within the front motor bearing.

118. In a mining machine, a portable support, a motor thereon having a rotatable casing disposed at the forward end thereof and having its power shaft horizontally disposed and extending longitudinally of the machine, and cutting mechanism driven by said motor including a rotatable cutter head rotatable with said casing and having a reduced neck journaled on said support at the forward end of said motor about an axis coincident with said shaft axis.

119. In a mining machine, a portable support, a motor mounted thereon at the forward end thereof and having its casing rotatable about a horizontal longitudinally extending axis, means for journaling said casing on said support comprising front and rear bearing means, said bearing means comprising cylindrical reduced portions ar-

ranged in axial alinement with the motor axis, and cutting mechanism driven by said motor comprising a cutter head secured to said rotatable motor casing and disposed in front of said front bearing means, said cutter head being connected to said motor casing solely by means extending through said front bearing means.

79

120. In a mining apparatus, a portable support, a coal cutting machine journaled thereon for rotation about a horizontal axis extending longitudinally of said support and comprising a motor and cutting and feeding mechanisms driven thereby, and means for effecting rotation of said machine relative to said support.

75

121. In a mining apparatus, a portable support, a coal cutting machine journaled thereon for rotation upon a horizontal axis extending longitudinally of said support and comprising a motor and cutting and feeding mechanisms driven thereby, and mechanism driven by said motor through said feeding mechanism for effecting rotation of said machine relative to said support.

85

122. In a mining apparatus, a portable support, a coal cutting machine journaled thereon for rotation upon a horizontal axis extending longitudinally of said support and comprising a motor and cutting and feeding mechanisms driven thereby, means for effecting rotation of said machine relative to said support, and mechanism driven by said motor through said feeding mechanism for propelling said support.

95

123. In a mining apparatus, a portable support, a coal cutting machine mounted thereon having a frame comprising a cutter section, a motor section, and a feed section, and means for mounting said machine on said support for rotation about its longitudinal axis comprising reduced bearing means disposed between said frame sections at the opposite ends of said motor, and means for rotating said machine relative to said support.

100

124. In a mining machine, cutting mechanism including a cutter head and a cutter bar pivotally mounted thereon, and means for journaling said bar on said head comprising a ring member secured to said bar and having a groove about its internal periphery, and a plate member secured to said head and projecting within said groove.

115

125. In a mining machine, cutting mechanism including a cutter head and a cutter bar pivotally mounted thereon, and means for journaling said bar on said head comprising a ring member secured to said bar and having a groove about its internal periphery, a plate member secured to said head and projecting within said groove, and a flange on said head engaging the inner periphery of said ring member.

CERTIFICATE OF CORRECTION.

Patent No. 1,786,243.

Granted December 23, 1930, to

MORRIS P. HOLMES.

It is hereby certified that error appears in the printed specification of the above numbered patent requiring correction as follows: Page 2, line 67, for "sleeve" read sleeves; page 4, line 42, for "Form" read From; page 5, line 88, for "213" first occurrence, read 212; page 10, line 47, claim 21, for "driven" read drive; line 81, claim 25, after the word "casing" insert a comma; line 85, claim 26, before "driving" insert the article a, and line 117, claim 30, for "co-operative" read co-operating; page 13, line 99, claim 69, for "casing" read frame; page 14, line 1, claim 73, after the word "bodily", and line 38, claim 77, after the word "including" strike out the comma; page 14, lines 41 to 43, claim 77, strike out the words "including transmission mechanism housed in said rotatable frame and" and insert same to follow after the word "means" in line 40, of same claim; page 16, line 106, claim 103, after the word "therefor" strike out the comma; page 17, line 37, claim 107, strike out the article "the" second occurrence; page 20, line 109, claim 145, for the word "support" read supports; and that the said Letters Patent should be read with these corrections therein that the same may conform to the record of the case in the Patent Office.

Signed and sealed this 3rd day of February, A. D. 1931.

(Seal)

**M. J. Moore,
Acting Commissioner of Patents.**

for rotating said cutter head about its axis relative to said supporting means.

147. In a mining apparatus, kerf cutting mechanism, adjustable supporting means for said kerf cutting mechanism including relatively adjustable front and rear wheeled supports, and mechanism for adjusting the wheels of said wheeled supports simultaneously in the same sense to change the elevation of said cutting mechanism and for adjusting the wheels of said wheeled supports in opposite senses to vary the angle in altitude of said cutting mechanism, and motor operated devices for driving the wheels of said supports irrespective of the relatively adjusted positions of said supports.

148. In a mining apparatus, a wheeled support including a frame adjustable into different elevations relative to the support wheels, and kerf cutting mechanism mounted on said frame including a cutter head rotatable about a longitudinal axis, and bearing means for supporting said cutter head on said frame including coaxial bearing members spaced a substantial distance apart longitudinally of said frame.

149. In a mining apparatus, a wheeled support including a frame adjustable into different elevations relative to the support wheels, kerf cutting mechanism mounted on said frame including a cutter head rotatable about a longitudinal axis, bearing means for supporting said cutter head on said frame including coaxial bearing members spaced a substantial distance apart longitudinally of said frame, and means for locking said cutter head in different positions about its axis within said bearing means.

150. In a mining apparatus, a wheeled support including a frame adjustable into different elevated positions relative to the support wheels, and kerf cutting mechanism mounted on said frame including a cutter carrying head rotatable about a longitudinal axis, a motor secured to said head and rotatable therewith, and bearing means on said frame for said head and motor including a bearing disposed between said head and motor and a second bearing disposed at the end of said motor remote from said head.

151. In a mining apparatus, a wheeled support including a frame adjustable into different elevated positions relative to the support wheels, and kerf cutting mechanism mounted on said frame including a cutter carrying head rotatable about a longitudinal axis, a motor secured to said head and rotatable therewith, bearing means on said frame for said head and motor including a bearing disposed between said head and motor and a second bearing disposed at the end of said motor remote from said head, and devices driven by said motor for rotating said head and motor about their axes relative to said frame.

152. In a mining apparatus, a wheeled support including a frame adjustable into different elevated positions relative to the support wheels, and kerf cutting mechanism carried by said frame including a cutter carrying head rotatable about a longitudinal axis, a motor secured to said head for rotation therewith, and bearing means between said cutting mechanism and said frame including a reduced bearing portion between said head and motor and a second reduced bearing portion at the end of said motor remote from said cutter head, and bearing means carried by said frame and within which said reduced bearing portions are rotatively mounted.

153. In a mining apparatus, a wheeled support including a frame adjustable into different elevated positions relative to the support wheels, and kerf cutting mechanism carried by said frame including a cutter carrying head rotatable about a longitudinal axis, a motor secured to said head for rotation therewith, and bearing means between said cutting mechanism and said frame including a reduced bearing portion between said head and motor and a second reduced bearing portion at the end of said motor remote from said cutter head, bearing means carried by said frame and within which said reduced bearing portions are rotatively mounted, and devices driven by said motor for rotating said cutter head and motor about their axes within said bearing means.

In testimony whereof I affix my signature. 100
MORRIS P. HOLMES.
